UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

FRICITION SHOCK-ABSORBING MECHANISM.

Application filed September 8, 1921. Serial No. 499,210.

To all whom it may concern:

Be it known that I, JOHN F. O'CONNOR, a citizen of the United States, residing at Chicago, in the county of Cook and State of Illinois, have invented a certain new and useful Improvement in Friction Shock-Absorbing Mechanisms, of which the following is a full, clear, concise, and exact description, reference being had to the accompanying drawings, forming a part of this specification.

My invention relates to improvements in friction shock absorbing mechanisms.

One of the objects of my invention is to provide an efficient railroad car draft rigging.

Another object is to provide a wedge for the friction parts that will have a high-wedging action and will be capable of easy release. Other objects will appear from the description of the embodiment of my invention hereinafter following and shown in the drawings.

In the drawings, Figure 1 is a horizontal section partly in top plan view, of a draft rigging embodying my invention. Fig. 2 is a cross-section taken on the line 2—2 of Fig. 1. Fig. 3 is a cross-section taken on line 3—3 of Fig. 1. Fig. 4 is a partial vertical longitudinal section taken on the line 4—4 of Fig. 3. Fig. 5 is a perspective view of one of the wedging elements. Fig. 6 is a perspective view of the wedging key. Figs. 7, 8 and 9 illustrate a modification in which a gear is shown that has a frictional shell circular in form instead of substantially rectangular as shown in the previous figures. In these, Fig. 7 is a front end elevation. Fig. 8 is a longitudinal vertical section taken on the line 8—8 of Fig. 7 and Fig. 9 is a horizontal section taken on line 9—9 of Fig. 7.

Referring to the form of my invention illustrated in Figs. 1 to 6 inclusive, the numerals 10 indicate draft members or parts of the car frame to which the draft rigging is applied. Rear stop members are shown at 11—11 and front stop members at 12—12. The drawbar 13 is provided with a transverse key 14 which passes through slots 15—15 in the yoke 16 making a sliding connection between the yoke and drawbar, the ends of the key extending through slots 17—17 in the front stop members and adjacent portions of the draft members. A

front follower is indicated by the numeral 18 and a tie plate or carrier 19 is bolted as at 20—20 to the draft members and is adapted to support the parts within the yoke.

The shell or casing 21 is interiorally provided with spring members comprised of the double coils 22—22 in twin arrangement, seated between the rear plate 23 of the shell and the spring follower 24. The spring follower engages the rear ends of the friction shoes 25—25 which are adapted each to frictionally bear against the adjacent friction liner 26. Between the friction-shoe is mounted a wedge mechanism 27 which includes the wedge-members 28—28 between 65 which is interposed the friction plate 29. The friction liners 26 are provided with the shoulders 30—30 which are adapted to engage between the internal shoulders 31—31 with which the interior forward portion of 70 the shell is provided. The wedge members 28—28 are each provided on their outer faces with a plurality of anti-friction roll seats 32—32 for the reception of the anti-friction rollers 33—33 which operate between 75 the said wedge member and the adjacent roll seats 34—34 provided upon the friction shoe 25. The wedge members 28 are each provided at their inner ends with an inwardly turned shoulder 35 against which the rear 80 edge 36 of the friction plate bears in normal position of the parts. The said friction plate 29 is a flat rectangular form and provided at its upper and lower ends with transversely extending, preferably convexed, guides 37 adapted to move longitudinally in the upper and lower ways 38 and 39, respectively, which are longitudinally arranged in the interior faces of the shell. The guides at their outer ends form shoulders 40—40 which are stepped back from 85 the front edge 41 of the friction plate 29 sufficiently to permit the engagement of the said shoulders 40 against the retaining flange 42 which forwardly terminates the 90 grooves 38 and 39 within the shell and to permit, when so engaged, the forward extension of the face 41 of the friction plate beyond the forward or open end of the shell 95 as illustrated in Fig. 1 of the drawings. In this position of the plate, it will be observed that the wedge members 28—28 are arranged to extend forwardly of the front edge of said plate in normal position of the parts. The grooves 38 and 39 are rear- 100 105 110

wardly closed by the upper and lower shoulders and stops 43 and 44 respectively, shown in detail in Fig. 4 of the drawings. In assembling the friction mechanism of the 5 gear, the liners 26 may be first inserted and then the friction plate may be inserted through the forward opening of the shell in a horizontal position and rotated into its vertical position in the grooves 38 and 39 between the limiting shoulders and stop or 10 stops at the ends thereof, hereinafter described. It will be noticed that the length of the guides 40 upon the friction plate is less than the length of the grooves 38 and 15 39, to permit a short sliding movement of the friction plate longitudinally of the shell. On rearward movement of the draw bar, the shell is held against retreat by the rear stop members 11, the front follower is 20 forced rearwardly pressing against the wedge members 28-28 of the wedge mechanism 27, which, together with the friction plate, moves rearwardly as a unit and through the medium of the anti-friction rollers operating upon the roll seats of the friction shoes, spreads the said shoes into frictional engagement with the shell liners, the 25 rearward movement of said shoes being yieldingly resisted by the springs pressing against the spring follower, which is interposed between them and the friction shoes. This spreading action continues until the guides 37 engage the rear stop shoulders in the grooves 38 and 39, and simultaneously 30 therewith the front edge 41 of the friction plate is at the mouth of the shell, in which position it obviously cannot be driven farther inward by the further rearward movement of the follower when the follower 35 has, as it may thereafter, come into engagement with the front end of the shell. Upon halting of the friction plate, the follower drives the wedge members 28 still farther rearwardly, each wedge member, however, 40 acting separately and sliding in frictional engagement upon the sides of the friction plate. Thus, if the total wedging angle of the wedge mechanism when the wedge members 28 and the friction plate 29 are moving together as a unitary wedge, has a given 45 angle upon the stoppage of the friction plate, each wedge member 28 will continue to act on its further movement, each having a wedging angle of one-half that of the wedging mechanism before the halting of the friction plate.

On release movement, the springs bear outwardly upon the spring follower, driving back the friction shoes 25 and carrying the wedge members 28 and the friction plate 29 outwardly as a single unit until the front shoulders 40 of the guides 37 engage against the shoulders or stops 42 arresting the outward movement of the friction plate and permitting the wedge members 28 to continue

to travel outwardly until their shoulders 35 engage the rear edge of the friction plate 29 when normal position of the parts is once more attained.

Upon forward movement of the draw bar, the front follower holds the wedge members 28 against forward movement, the shell is moved forwardly by the yoke and action of the parts is attained within the shell similar to that hereinbefore described in connection with the rearward movement of the draw bar, as will be well understood.

In the modified form, shown in Figures 7, 8 and 9 of the drawings, the front portion of a friction shell is indicated by

80 the numeral 70 having within it the usual springs, not shown, the spring follower 71, the friction shoes 72 annularly arranged within the shell, and wedge members 73-73, 85 having interposed between them the friction plate 74. Between each of the wedge members 73 and the adjacent friction shoes 72 an anti-friction roller 75 is mounted. The shell shown in the modified form, it will be noted, is circular in cross section and the plate 74 is provided with upper and lower guides 76 which operate in the ways 77 and 78, respectively, provided in the shell. The said ways are forwardly closed by the shoulders 79-79 and rearwardly closed by similar shoulders 80-80 which form stops for the upper and lower projections 81 and 82 with which the friction plate 74 is provided to limit its forward and rearward movement. The friction plate 74 and other parts are assembled in a manner similar to that employed in assembling parts of the device shown in Figures 1 to 5 inclusive. The action of the parts is the same as in the preferable form, the chief difference between the modified form and the preferred one being that in the modification no liner is used for the shell; the friction part of the shell is circular instead of generally rectangular in cross section; the wedging key protrudes less from the shell, and the wedge members each employ a single anti-friction roller instead of a plurality of rollers.

100 I have herein shown and described what I now consider the preferred manner of carrying out the invention, but the same is merely illustrative and I contemplate all changes and modifications that come within the scope of the claims appended hereto.

110 I claim:

1. In a friction shock absorbing mechanism, the combination with a friction shell; of friction shoes within said shell; a pair of wedge members co-acting with said shoes; a movable friction element interposed between said members, said element being provided with guides, and said shell being provided with ways to receive said guides, said ways being provided with stops to limit the

movement of said guides; and a spring resistance opposing inward movement of said shoes.

2. In a friction shock absorbing mechanism, the combination with a shell having interior friction surfaces; of friction shoes within said shell, said shoes being adapted to co-act with said interior friction surfaces; a pair of friction wedge members; a spring resistance; and a friction element mounted between said members, said friction element being provided at its ends with guides and said shell being provided with ways to receive said guides, said ways being provided with shoulders at the outer ends thereof to limit the outward movement of the friction element.

3. In a friction shock absorbing mechanism, the combination with a shell having interior friction surfaces; of friction shoes within said shell; a pair of wedge members co-acting with said shoes; a spring resistance for said shoes; and a friction element mounted between said members, said friction element being provided at its ends with convex guides and said shell being provided with concave ways to receive said guides, said ways being provided with shoulders at the outer ends thereof to limit the outward movement of the friction element.

4. In a friction shock absorbing mechanism, the combination with a shell; of friction shoes within said shell; a spring resist-

ance co-acting with said shoes; a follower interposed between said spring resistance and said shoes; a pair of wedge members co-acting with said shoes; a front follower engaging said wedge members; and a friction element interposed between said members, said friction element being spaced from both of said followers, said element and said shell being provided with co-operating guides and ways, said ways being provided with stops to limit the movement of the friction element.

5. In a friction shock absorbing mechanism, the combination with a shell provided with interior friction surfaces; of friction wedge shoes in said shell coacting with said friction surfaces; a pair of wedge members coacting with said shoes; a longitudinally movable friction element mounted between said members, said element and said shell being provided with coacting stops for limiting the inward and outward movement of said element with reference to the shell; and a spring resistance for said wedge shoes.

In witness that I claim the foregoing I have hereunto subscribed my name this 31st day of August, 1921.

JOHN F. O'CONNOR.
